UNITED STATES PATENT OFFICE.

JAMES A. TAYLOR, OF RICHMOND, KENTUCKY.

COLLAR BUTTON AND TIE HOLDER.

Application filed February 27, 1926. Serial No. 91,181.

This invention appertains to collar buttons and the primary object of the invention is to provide a novel attachment for connection with the head of an ordinary collar button for engaging a tie or scarf for holding the tie or scarf in correct position relative to the collar.

Another primary object of the invention is the provision of a shell shaped to conform to the configuration of the head of a collar button and adapted to snap thereon and provided with a suitable pin for engaging the knot of the tie to hold the tie in place relative to the collar.

Another object of the invention is to provide novel means for forming the pin so as to prevent slipping of the tie from off of said pin.

A further object of the invention is to provide a novel tie holder attachment for collar buttons, which can be readily associated with a collar button and placed upon the market at a low cost.

With these and other objects in view, the invention consists in the novel construction, arrangement and formation of parts, as will be hereinafter more specifically described, claimed, and illustrated in the accompanying drawings, in which drawings:

Figure 1 is a top plan view of a collar button showing the improved attachment connected therewith.

Figure 2 is a side elevation of a collar button showing the improved attachment connected therewith,

Figure 3 is a detail section taken on the line 3—3 of Figure 2 illustrating the means of connecting the attachment with the head of the button,

Figure 4 is a transverse section through the attachment illustrating the means of connecting the same to the head of the button.

Figure 5 is a bottom plan view of the attachment,

Figure 6 is a longitudinal section through the attachment showing the same connected with a button,

Figure 7 is a longitudinal section through the attachment prior to the connection thereof with a button.

Referring to the drawings in detail, wherein similar reference characters designate corresponding parts throughout the several views, the letter A generally indi-

cates a collar button and B the novel tie holding attachment therefor.

The collar button A can be of any conventional form and embodies the base 10, the stud 11 connected therewith and the head 12. The head 12 can be of any desired shape and rigidly connected with a stud 11 or can be connected with the stud by a suitable hinge, in order that the head, when the same is of an elongated character, can be placed parallel with the stud.

The improved attachment B is adapted to be struck from a single blank of sheet metal and comprises a shell 15 which is shaped to conform to the configuration of a button head with which the same is associated. The shell 15, as shown, is of an elongated character and gradually narrows toward one end thereof. The side longitudinal edges of the shell 15 are provided with lips 16 which can be of a resilient character for snapping over the head of the button, or as shown, the same can be of a bendable character to permit the same to be bent back over the inner face of the head 12 as clearly shown in Figures 3 and 4. The shell 15 at the central portion thereof is provided with an elongated opening 17 and arranged longitudinally of the opening equi-distant of the side walls thereof is a tie engaging pin 18, which is formed integral with the shell at one end wall thereof.

The pin 18 has the free end thereof provided with a penetrating point 19 and in order to prevent the disengagement of the tie from the pin, after the same has been inserted in the knot thereof, the pin is provided at a point intermediate its ends with a struck in lug or rib 20 which is adapted to abut the head of the collar button. The attachment B can be sold independently of the collar button and snapped on the head thereof by the user and can be exchanged from one button to the other.

If preferred the attachment can be permanently connected to the button by having the tongues or lips 16 formed of relatively stiff material.

From the foregoing description, it can be seen that a novel attachment has been provided for the head of the collar button for permitting the effective holding of a tie in place relative to a collar.

Changes in details may be made without departing from the spirit or the scope of this invention, but what I claim as new is:

- 2
1. As a new article of manufacture, a tie holding attachment for collar buttons comprising a shell shaped to conform to the configuration of the head of a collar button, ⁵ means carried by the shell for gripping the head of a button, a longitudinally extending pin carried by the shell at the longitudinal center thereof, and a struck in lug formed on the pin at a point intermediate the ends ¹⁰ thereof.
  2. The combination with a collar button including a base, a stud and a head, of a tie holding attachment for the collar button comprising a shell shaped to conform to the ¹⁵ configuration of the head, lips formed on the shell for engaging the head, the shell having a centrally disposed elongated opening therein for disposing a part of the outer face of the head of the button, a pin formed integral ²⁰ with the shell and lying longitudinally within said opening having the penetrating point thereof spaced a predetermined distance from one wall of said opening.
  3. The combination with a collar button comprising a base, a stud and a head, of a ²⁵ tie holding attachment for the collar button comprising a shell shaped to conform to the configuration of the head for receiving the exterior face thereof, retaining lips formed on the side edges of the shell for engaging ³⁰ the inner face of the head, the shell having an elongated opening formed therein to partially expose the exterior face of the head, a pin disposed centrally within the opening ³⁵ connected at one end to the shell, the penetrating point of the pin being spaced a predetermined distance from one end wall of the opening formed in said shell, and a struck in resilient lug formed on said pin for engaging the exterior face of said head. ⁴⁰

In testimony whereof I affix my signature.

JAMES A. TAYLOR.
